CLAIM

The ornamental design for the recycling bin, as shown and described.

DESCRIPTION

This application is related to commonly assigned, concurrently filed application Ser. No. 29/333,947.

FIG. 1 is an isometric view of the recycling bin of the present design;

FIG. 2 is a front elevation view thereof;

FIG. 3 is a right side elevation view thereof, the left side elevation view being a mirror image thereof;

FIG. 4 is a top plan view thereof;

FIG. 5 is a rear elevation view thereof;

FIG. 6 is a isometric view thereof in a first environment; and,

FIG. 7 is an isometric view thereof in a second environment.

The broken lines showing in FIGS. 6 and 7 is included for the purpose of illustrating environment and forms no part of the claimed design.
